JACK STAND

George P. Edgell, Sr., Harrison, Ark., assignor to W. J.
Stout Company, Inc., Western Grove, Ark.

Filed Oct. 16, 1972, Ser. No. 297,854

Term of patent 14 years

Int. Cl. D12—05

U.S. Cl. D12—55

FIG. 1

FIG. 2

FIG. 3

FIG. 5

FIG. 4

FIG. 1 is a side elevational view of the jack stand embodying my new design;

FIG. 2 is a view similar to FIG. 1 showing a portion of the stand extended;

FIG. 3 is another side elevational view thereof;

FIG. 4 is a top plan view thereof; and

FIG. 5 is a bottom plan view thereof.

I claim:

The ornamental design for a jack stand, as shown.
